UNITED STATES PATENT OFFICE.

LIONEL ALFRED WHARRAD, OF REDDITCH, ENGLAND.

NEEDLE SCOURING AND POLISHING MACHINE.

1,265,564.

Specification of Letters Patent. Patented May 7, 1918.

Application filed January 30, 1917. Serial No. 145,532.

To all whom it may concern:

Be it known that I, LIONEL ALFRED WHARRAD, a subject of the King of Great Britain, residing at No. 5 Peakman street, 5 Redditch, in the county of Worcester, England, have invented certain new and useful Improvements in Needle Scouring and Polishing Machines, of which the following is a specification.

10 My invention relates to machines for the scouring and polishing of needles, knitting pins and other wires or shafts of the kind in which the needles or other articles are wrapped with emery and oil in packets of 15 harden or other strong fabric and are subjected to a rolling operation between pressure rollers for the purpose of causing the needles or the like contained in the packets to roll one against another and by mutual attrition to effect the polishing of the 20 said needles, and my invention consists of the construction and arrangement or combination hereinafter described of the parts of such machines whereby they are simplified 25 and rendered very efficient.

In carrying my invention into effect I prefer to employ a set of three rollers for each packet of needles to be treated, namely two lower rollers the axes of which may be 30 stationary as is usual in ordinary three roller machines for the scouring and polishing of needles, the said lower rollers being driven by belt, rope or other gearing so as to effect the rotation of the packet or 35 bundle of needles while under treatment and an upper floating or pressure roller which is by the action of a hand lever or other means brought to its bearing on the packet or bundle of needles which is supported on the two lower rollers, so as to exert the desired pressure thereon, the said upper floating or pressure roller when the machine is at work receiving a rotary motion through its contact with the packet or 45 bundle of needles which is rotated by the lower rollers.

Mechanical means are combined with the upper or floating pressure roller for giving it an intermittent regular or irregular slight 50 movement toward the axis of the packet or

bundle of needles during the rotation of the same so as to effect a kneading operation on the packet or bundle of needles or the like.

The mechanical means for effecting the said intermittent slight movement of the 55 upper or floating pressure roller toward the axis of the packet may consist of a cam arranged to bear on the middle or other part of the upper floating or pressure roller the said cam having one, two or more rises of 60 regular or irregular shape. The lifting of the upper floating or pressure roller to its normal position when a rise of the cam is passing from off the roller is effected by the inherent tendency to resume its normal size 65 and shape possessed by the packet or bundle under treatment. The ends of the upper floating or pressure roller are so arranged that the said roller can partake of a wabbling or rocking motion if desired. 70

I will further describe my invention in connection with the accompanying drawings.

Figure 1 is a diagram illustrating the respective positions of the rollers and packet 75 or bundle of needles under treatment and the cam which contacts with the upper floating or pressure roller and effects such movement of the same during its rotation that the desired kneading action on the 80 packet or bundle of needles is obtained.

Fig. 2 represents partly in end elevation and partly in section a needle scouring and polishing machine containing my improvements and Fig. 3 is a front elevation of a 85 portion of the said machine.

The same letters of reference indicate the same parts in the several figures of the drawings.

a are the lower rollers which are capable 90 of a rotary motion only and are driven in any ordinary way. *b* are the upper floating or pressure rollers and *c* are cams free to rotate on the spindles *d* situated over and parallel with the upper floating or pressure 95 rollers *b*. The cams *c* are also capable of a sliding adjustment on the spindles *d*. The requisite pressure on the spindles *d* may be obtained in various ways. In the arrangement shown the ends of the spindles 100

d are connected by rods *e* and springs *f* with rods or tubes *g* situated under the table or bed of the machine, the rods *e* passing through the spindles *h* on which the upper floating or pressure rollers *b* rotate. On the rods or tubes *g* a yoke-like part *i* is arranged the said yoke-like part being connected to a lever *k* pivoted at *l* to the frame of the machine, the free end of the lever *k* carrying a pawl *m* which in conjunction with the rack *n* fixed to the other side of the frame of the machine serves to retain the lever *k* in any position to which it may be adjusted. The lever *k* has depending from its free end a rod *p* terminating in a loop or stirrup *r* whereby the attendant may by inserting his foot in the stirrup *r* and applying a downward pressure to the rod *p* exert the required pressure on the packet or bundle of needles *s* which has been introduced between the rollers of the machine. Should, under the operation of the machine, the bundle or packet tend to thicken at one or other end it will only be necessary for the attendant to adjust the cam *c* on the spindle *d* so as to bring it to bear on the roller *b* nearer the end operating on the thicker part of the packet or bundle.

I wish it to be understood that I do not limit myself to the mechanical means hereinbefore described and illustrated for obtaining the positive movement of the roller toward the packet or bundle of needles under treatment during the rotation of the roller.

Although machines containing my improvements may be constructed to operate on single packets only, I prefer to arrange the rollers in two or more sets arranged one behind the other as represented in Fig. 2, and if desired two or more series of rollers in line may be employed in which case the lower rollers which as is usual are the driven rollers, are provided with the necessary driving gear (not shown) at the extreme ends of the long common shafts of the series of rollers *a* in line.

And although my invention is primarily intended to dispense with rollers such as are referred to in the specification of Baylis's 50 U. S. Patent No. 1180226, April 18, 1916, I wish it to be understood that an upper floating or pressure roller *b* such as is hereinbefore described and represented with cam *c* may be used in combination with lower rollers such as are described and represented in Baylis's patent specification with great advantage to the prior patented machine.

In order to facilitate the introduction of the packets or bundles of needles into the machine and the removal and replacement of packets which have been under treatment a sufficient length of time I arrange at the back of the machine an inclined plane *t* in

such a position with respect to the rear set of rollers that when a bundle or packet *u* is 65 placed on the said inclined plane as is indicated in dotted lines in Fig. 2 and pressure is applied thereto by the attendant it will force from between the rear set of rollers the packet which is situated between them and 70 the displaced packet will be carried against and will effect the displacement of the packet or bundle of needles in the middle set of rollers and so on the packets being removed and replaced in the manner which 75 will thus be readily understood. During the operation of removing and replacing the bundles or packets of needles the pressure on the upper floating rollers is removed or reduced to a minimum and the rotation of 80 the upper floating or pressure rollers is preferably arrested by the pressure of the hand of the operator thereon.

Although I have illustrated my invention as being carried into effect by the positive 85 or mechanical movement of the upper floating or pressure roller with respect to the packet or bundle of needles under operation I wish it to be understood that I do not limit myself thereto as the kneading action may 90 be effected by the mechanical or positive movement of one or other or both of the lower rollers or of the whole set of rollers. The more frequently the kneading movements are repeated the more efficiently and 95 quickly will the scouring and polishing of the needles be effected.

And although I have described my invention as a needle scouring and polishing machine I wish it to be understood that the 100 same may be used for scouring and polishing knitting pins and other similar articles and metallic wires or shafts generally.

I claim:—

1. In a needle scouring and polishing 105 machine, the combination of lower rollers having a fixed plane of rotation and arranged to support and have contact with a packet or bundle of needles, and an upper roller mounted to have a floating resilient 110 movement and free to move downwardly toward and upwardly from the lower rollers in contact with the packet or bundle of needles and also provided with means having direct contact with the upper portion of 115 the surface thereof for giving it a positive downward movement at intervals for setting up a kneading action on the packet or bundle of needles.

2. In a needle scouring and polishing 120 machine, the combination of lower rollers disposed in alinement and having fixed planes of rotation and arranged to support and contact with a packet or bundle of needles, an upper resiliently controlled 125 floating pressure roller disposed over the

lower rollers and also contacting with the packet or bundle of needles under treatment, and a cam directly engaging the upper portion of the surface of the upper roller and having cam projections which impart to the latter roller a positive downward movement at intervals to set up a kneading action relatively to the packet or bundle of needles,

the resiliency of the packet or bundle of needles causing the upper roller to rise at 10 intervals when liberated from the maximum cam pressure thereon.

In testimony whereof I have hereunto set my hand.

LIONEL ALFRED WHARRAD.
